UNITED STATES PATENT OFFICE.

JOHN MAGEE, OF NEW YORK, N. Y., ASSIGNOR TO BIGELOW CARPET COMPANY, OF CLINTON, MASSACHUSETTS.

DESIGN FOR A CARPET-PATTERN.

Specification forming part of Design No. 5,300, dated October 3, 1871.

To all whom it may concern:

Be it known that I, JOHN MAGEE, of the city of New York, in the county and State of New York, have invented a new and original Design for a Carpet; and I do hereby declare that the following is a full, clear, and exact description thereof, which will enable others skilled in the art to make and use the same, reference being had to the accompanying photographs forming part of this specification.

The photographs represent my new design.

This invention relates to a new design for the center-piece, and also to a new design for the surrounding scroll-work of a carpet-pattern.

The center piece A is of peculiar external configuration and contains a series of decorative borders and fillings, as shown. The scroll-work B surrounding it shows foliage gracefully intertwined in an artistic and original manner.

I claim as my invention—

1. The design for a center piece A, as shown.
2. The design for the surrounding scroll-work B, as shown.

The above specification of my invention signed by me this 11th day of August, 1871.
